UNITED STATES PATENT OFFICE.

STEPHEN HAINES PLUM, 2d, OF MADISON, AND AMOS ACKLEY, OF CAMDEN, NEW JERSEY, ASSIGNORS TO AMERICAN TYPE FOUNDERS COMPANY, A CORPORATION OF NEW JERSEY.

TRIPPING MECHANISM FOR PLATEN PRESSES.

Original application filed February 11, 1925, Serial No. 8,441. Divided and this application filed July 30, 1925. Serial No. 47,139.

This invention relates to automatic printing machinery, and has particular reference to an automatic tripping mechanism for job platen presses of the type of the Chandler and Price job press. More particularly this invention relates to a tripping mechanism such as is disclosed in our pending application for a patent filed February 11, 1925, Serial No. 8441 of which this application 10 is a division.

In some respects this invention also refers to certain improvements in the automatic feeding mechanism disclosed in the U. S. Patent No. 1,476,829 dated December 11, 15 1923, to L. E. Morrison.

The object of this invention is to provide a tripping mechanism of generally improved character and containing certain novel features of construction and operation adapted 20 to cooperate with the mechanisms disclosed in said application and patent. Accordingly this invention comprises such features, arrangements and combinations of parts as are hereinafter set forth while reference is 25 had to the accompanying drawings in which—

Fig. 1 is a side view of a platen press equipped with an automatic feeding mechanism embodying the invention, with parts 30 omitted and parts broken away.

Fig. 2 is a fragmentary view of a portion of the press which has been omitted in Figure 1.

Fig. 3 is a detailed side view of parts of 35 the tripping mechanism shown in Figure 1.

Fig. 4 is a plan view of Figure 3.

Figs. 5 and 6 are detail views of parts shown in Figure 3.

Fig. 7 is a plan view of the tripping mechanism with parts omitted and broken away.

Fig. 8 is a detail view of parts of the tripping mechanism.

Fig. 9 is a detail view of parts shown in Figure 7.

The press itself is illustrated only in outline as it is a well known machine in the art. The frame of the press is designated 3, the driving shaft 4. 5 is the platen pivot, 6 the platen and 7 the form member. 9 and

10 are the usual connecting rods and 11 the 50 platen locking cam. The connecting rod 9 appears in Figures 1 and 2, and the connecting rod 10 appears in Figure 7. 13 indicates the tripping means in Figure 1 and 14 the tripping lever pivoted at 12. All of the 55 aforesaid parts, their construction and operation are well known in the art and require no further description or illustration.

The paper 15 to be printed is supported on an inclined feed table 18 which rests on suitable side brackets 20 secured to the press.

The top sheet is separated from the pile and conveyed to the platen by suction nozzles. The details of the suction nozzle and the separating mechanism is fully disclosed in the aforesaid pending application to which reference is made. For the purposes of understanding the operation of the tripping mechanism it suffices to point out that the suction nozzle is in the form of a 70 suction cup 53 suitably carried on a nozzle support 57. The nozzle support 57 is clamped to a shaft 72 which is journaled in the swinging arms 75 and 76 one on each side of the feed table. The arms 75 and 76 75 are pivoted on a shaft 67 which is supported in suitable brackets 68 and from the said shaft extends the elements marked 66 and which constitute a transfer table. The upper ends of the arms 75 and 76 are connected by a tube 77 and a rod 78.

The arrangement is such that the arms 75 and 76 oscillate on the said shaft 67 from the position shown in Figure 1 where the nozzle 53 picks up the top sheet after which 85 the arms move to the left in the said figure to convey the sheet and deposit it upon the transfer table 66 from which it drops upon the platen when the latter is in its sheet receiving position as will be understood.

The arms 75 and 76 are operated from the connecting rod 10 by means of a link 98 pivoted to a bell crank 100 which in turn is pivoted at 96 to a casting 95 suitably supported on the press. The numeral 91 denotes a rock shaft, one end of which is connected by links 93 and 101 to the aforesaid bell crank 100. The other end of the rock

shaft carries an arm 90 which is connected by a link 89 to the arm 75. Suction is applied to the nozzles by means of a suction air pump 106 pivoted to the said casting 95. The pump piston stem 107 is pivoted to the connecting rod 10. From the pump 106 an air hose 108 leads to a valve chest 109 and from the latter a hose connection 110 leads to the hollow tube 77 and from the latter hose connections 52 lead to the suction nozzles.

All of the aforesaid elements are disclosed in detail in the aforesaid pending application to which reference is made for 15 complete detailed understanding for the operation for separating the top sheet from the pile and conveying to the platen and the reference numbers used herein are the same as used in the said application for the same 20 elements to facilitate reference thereto.

Means are provided for tripping the press when the suction nozzles fail to pick up a sheet for any reason. Referring to Figures 1 and 2 the form member 7 is connected in 25 the usual manner to an eccentric shaft 130 by means not shown. 131 is an arm secured to the shaft and the arm 131 is connected by a link 132 to another arm 133 fast to a shaft 134. The latter carries a slotted arm 135. 136 is a pin which moves in the slot in arm 135. The pin is fast in a locking arm 137 mounted on a second shaft 138. Outside the frame the shaft 138 carries an arm 139 connected by a link 140 to the tripping lever 14 which is pivoted at 12. The foregoing describes the well known Chandler & Price job press tripping mechanism.

When the tripping lever 14 is moved to the left in Figure 1 by the operator, the 40 shaft 138 is rotated anticlockwise. The shaft 134 is rotated clockwise. The link 132 is lifted and swings the arm 131 to rotate the eccentric shaft 130 to trip the form. All in a well known manner.

45 This invention provides automatic means for operating the tripping lever 14 to trip the press. Referring first to Figures 1 and 8, the tripping lever 14 is provided with two headed pins 140 and 141 which support a trip latch 142 in the form of a thin flat piece of metal having a handle 143 at its upper end and a cam 144 at its lower end. The trip latch is held in normal inactive position as in Figure 1 by the said pin 140 which passes through an L shaped slot 145. At its lower end the trip latch has a straight slot 146 through which the lower pin 141 passes. The trip latch 142 is bent as at 147, Figure 8, to provide a pocket 148 between itself and the tripping lever 14, and within said pocket slides a trip hook lever 149 which is pivoted at 130 on the form member on the outside thereof. The lever 149 has a hook 150.

Normally the trip hook lever moves with 65 the form member and slides idly back and forth in the said pocket 148 and is prevented from engaging the lower pin 141 because the said lever rides on the said cam 144. Means, to be hereinafter described, 70 are provided for knocking the trip latch 142 off the upper pin 140, and the trip latch will then slide down until the upper edges of the two slots 145 and 146 come to rest on the pins 140 and 141. Thus the pin 141 is 75 exposed and on the rearward stroke, to the left in Figure 1, of the form member the hook 150 on the lever 149 will catch the lower pin 141 and pull the tripping lever into tripping position to the left, the same 80 as if it had been moved by hand. The automatic tripping means herein causes the trip latch 142 to be knocked off or pushed off the pins 140 and 141 to permit the hook lever 149 to engage and operate the tripping lever when the suction nozzles fail to pick up a sheet.

Referring to Figures 3 to 6, on each side of the paper feed table 18 there is provided an upstanding bracket 31 and 32 90 which suitably support a tube 30. Within the latter is located a second tube or hollow shaft 152, which at its one end adjacent the bracket 32 carries a handle 153. Below the shaft 152 the handle has a hook 154. The bracket 32 has secured thereto a fixed bearing 155 and on the latter there is pivoted at 156 a bell crank lever having its two branches or arms in two different planes. One arm 157 extends in under the handle 100 153 and is formed with a stop notch 158. The other arm extends outside of the feed table, see Figure 7, and downwardly and carries a pin 160. The bell crank 157—159 is held in normal inactive position as shown 105 in Figure 1 by a spring 161 which holds the arm 157 up against a pin 162 on the aforesaid bearing 155, and which spring therefore also holds the pin 160 in the arm 159 against or in touch with the handle 143 of the trip 110 latch 142, Fig. 1.

The bell crank arm 159 is connected by a link 163 to an upstanding arm 164 having a hook 165. The arm is pivoted on the shaft 67. On the nozzle carriage arm 76 115 there is pivoted on rod 78 a trip cylinder 166 which is a very small cylinder having a piston, not shown, to which is secured a piston stem 167. The latter is pivoted at 168 to a trip catch lever 169 pivoted at 170 to the arm 76. The trip catch lever and the piston stem 167 are held in normal 120 downward position on a stop pin 171 by means of a spring 172 which acts against a pin 173 in the trip catch lever. The catch lever has a hook 174 adapted to engage the aforesaid hook 165. To the shaft 67 and adjacent the said arm 164 there is affixed 125

cam 175 which lies in the path of the pin 173 which moves with the nozzle carriage arm 76.

Coiled around the said tube or shaft 152, Figure 4, is a spring 176 which engages the handle 153, Figure 5, and tends to turn said handle and shaft in a clockwise direction in Figures 3 and 5, and thus keeps the handle hook 154 in engagement with the stop 10 notch end 158 of the bell crank arm 157. A pin 177, Fig. 5, limits the movement of the handle 153.

Referring now to Figures 7 and 9, it will be seen that on the opposite end of the hollow shaft 152 there is secured an arm 180 which has a pin 181 adapted to engage the valve opening arm 119.

The operation of the automatic tripping means is as follows:—Referring to Figure 20 3 it will be seen that during the normal operation, as the nozzle carriage swings from the paper to the platen, the hook 174 on the trip catch lever would engage the hook 165 on the upstanding arm 164, move 25 the latter to the left and through the link 163 operate the bell crank 157—159 to actuate the trip latch and trip the press.

However, this does not occur, because when the suction is applied to the nozzles, 30 it is also applied to the trip cylinder 166 through a hose 183 connecting the cylinder to the hollow rod 77, Figure 3, hence the piston and piston stem 167 is pulled up and the hook 174 is moved upwards out of the 35 way of the hook 165, and of course the latter and the arm 164 do not move, hence the press is not tripped.

When, on the other hand, the suction nozzles fail to pick up a sheet, there is of 40 course no vacuum created in the pipe system between the pump 106 and the nozzles and the trip cylinder 166, consequently, the piston stem 167 is not lifted, the trip catch lever 169 is not lifted and as the 45 nozzle carriage swings to the left in Figure 3 towards the platen, the hook 174 engages the hook 165, and moves the latter to the left with the arm 164. Consequently the link 163 operates the bell crank 157—159 50 and the pin 160 pushes the trip latch off its pins and the hook lever 149 engages the lower pin 141 and trips the press.

At the same time, however, the bell crank arm 159 is moved rearward as aforesaid, 55 the bell crank arm 157 is moved down as shown in Figure 5 until the stop notch end 158 rests on the pin 162. Thus the spring 176 is free to move the handle 153 in over the arm 157 as shown. That is to say, when 60 the automatic trip operates, the handle 153 and hollow shaft 152 are automatically rocked or moved so that at the other end of said shaft, the pin 181 may operate the valve arm 119 to permanently open the valve

118. As the nozzle carriage continues its 65 rearward movement, the pin 173 rides up or over and on the fixed cam 175 to lift the hook 174 off from the other hook 165, see Figure 6.

To sum up:—When the nozzles fail to 70 pick up a sheet, the trip catch lever 169 remains in its downward position, the two hooks 174 and 165 engage momentarily, long enough to operate the bell crank 157—159. The latter then causes the trip to be operated 75 and also causes the vacuum to be permanently broken by opening valve 118 so long as the tripped condition is permitted to continue.

If such tripped condition is permitted to 80 continue, the press will of course continue to operate, but the nozzles will not pick up any sheets, and as the nozzle carriage swing back and forth, the two hooks 174 and 165 will each time momentarily engage but 85 nothing further will happen. After the trouble has been attended to, the handle 153 is manually moved rearward, that is, the handle hook 154 is moved back to the position shown in Figure 3, and the bell crank 90 157—159 will immediately be moved up into normal position as in Figure 3 by the spring 161 and the parts are again in normal working positions. The operator then of course moves the tripping lever 14 back into normal untripped position and at the same time 95 with his hand raises the trip latch back upon the pins 140 and 141.

In connection with the tripping mechanism it should also be noted that while the 100 press is tripped, the hook lever 149 continues to slide back and forth on the cam 144 but causes no further movement of the tripping lever 14 having already moved it into tripping position. Also, of course, that when 105 the handle 153 is operated to reset the tripping means, the pin 181 is moved away from the valve lever 119 and the valve 118 is closed by its spring. The tripping mechanism is then ready to operate should for 110 any reason the nozzles again fail to pick up a sheet.

The tripping mechanism also includes 115 means for tripping the press in the event the delivery grippers fail to seize a printed sheet to remove it from the platen. Referring to Figure 3 so much of the delivery gripper is shown as is necessary to understand the tripping mechanism referring thereto. A full disclosure of the gripper 120 and its operating mechanism is shown in the pending application referred to. For the purpose of this disclosure it is sufficient to state that the delivery gripper comprises a lower gripper jaw 230 and an upper gripper jaw 241 which are suitably supported on a gripper bar 193, Figure 1, carried by a suitable guiding support 192 which slides

on a fixed rod 195. The support 192 is provided with a guide way 198 in which moves a roller 200 on the end of an arm 201. The arm is fast to a rock shaft 202, and the rock shaft 202 is operated by means of a short arm 203 and a link 204 connected at 205 to a slotted cam 206 actuated by a stud 207 which connects the connecting rod 9 to the platen locking cam 11. The cam 206 is 10 suitably pivoted to the frame 20 at 208, all as shown in Figure 1. The arrangement is such that the gripper on the bar 193 moves toward and away from the platen in synchronism with the movements of the press, 15 but when for any reason the gripper fails to seize the printed sheet on the platen the tripping mechanism is automatically operated to trip the press.

To this end there is pivoted on the upper 20 gripper jaw at 252 a trip dog 253 having a weighted head 254 and a tail 255. When the gripper is open the trip dog rests by gravity on a pin 256 in the upper gripper jaw. When the gripper closes the dog is 25 of course thrown upward and becomes inactive in that then the tail 255 of the dog is lowered and the weighted head 254 then rests on top of the sheet which has been seized by the gripper. If the gripper does 30 not seize a sheet the dog tail 255 will be automatically elevated as in Figure 3 the moment the grippers leave the platen. This slight oscillatory movement of the trip dog is utilized to actuate the tripping mechanism 35 whenever necessary.

Between the paper pile and the platen there is hung a gripper trip 260 which is a thin piece of metal extending across the feeder, see Figures 1 and 7. The trip 260 fast on a shaft 261 carries an upstanding arm 262, which is connected by a link 263 to a hooked arm 264 pivoted on the aforesaid bearing piece 155, see Figures 3 and 5. The arm 264 normally hooks in over 45 a pin 265 fast on a finger 266 carried by a shaft 267 which lies inside the aforesaid hollow shaft 152 within the tube 30. The shaft 267 also carries a handle 268. On the other end of the shaft there is secured an 50 arm 269 having a pin 270. The pin 265 is held in under the hooked arm 264 by a spring 271, Figure 3.

The operation is as follows:—If the gripper seizes a sheet, the trip dog tail 255 will 55 remain lowered and on the delivery stroke pass under the gripper trip 260 without touching it. If the gripper fails to seize a sheet as in Figure 3, the tail 255 will be raised and on the delivery stroke strike the 60 trip 260 passing thereunder. Consequently, the shaft 261 will be rocked slightly and through the link 263 the hook arm 264 will be moved away from the pin 265, wherefore the shaft 267 will be rotated slightly by the

spring 271. This movement is sufficient to 65 cause the pin 270 on the other end of the shaft to open valve 118 in the valve chest. This of course breaks the vacuum in the suction nozzles, and this condition having 70 been brought about, the press will be tripped as described in connection with the tripping mechanism above. The resetting is accomplished by moving both handles 268 and 153 back into original normal position. The reason for this indirect way of operating the tripping mechanism when the grippers fail to deliver is, that it is impractical to construct the gripper trip device 75 strong enough to pull directly on the tripping means at 159 to knock the trip latch off the tripping lever 14. It should also be borne in mind that the tripping mechanism on a job press is a delicate device, which nevertheless must be arranged and constructed to act instantly whenever troubles 80 occur requiring tripping. The objects have been accomplished by the aforesaid tripping means.

The invention has been disclosed in its preferred form, but it is to be understood that nothing hereinbefore stated is to be construed as a limitation, because changes and alterations may easily be made by those skilled in the art without departing from the spirit of the invention or the scope of 95 the appended claims.

We claim:—

1. The combination of a platen press tripping mechanism, a tripping lever for actuating the same, a link for operating said tripping lever, a member carried by the latter for maintaining said link in normal nonoperating position with respect to the said tripping lever, mechanism for removing said member away from the said link to cause the press to be tripped and suction operated means for actuating the said removing mechanism. 100

2. The combination of a platen press tripping mechanism, a tripping lever for actuating the same, mechanism for operating said tripping lever comprising a suction cylinder, means operated by the latter for causing said tripping lever to trip the press, and suction operated means for actuating the said suction cylinder. 110

3. The combination of a platen press, a paper feeding device therefor comprising a paper feed table, paper separating means mounted on said table, a tripping mechanism for said press, devices for causing said tripping mechanism to trip the press and means mounted on said paper feed table and operated by said paper separating means for actuating the said devices. 120

4. The combination of a platen press, a tripping mechanism therefor, a tripping lever for operating said mechanism, suction 125

operated paper separating means, devices for causing said tripping lever to act, a gripping mechanism, and means on the latter for actuating said suction operated separating means to operate the said devices to effect the tripping of the press.

5. The combination of a platen press, a tripping mechanism therefor, a tripping

lever for operating said mechanism to trip the press, paper separating means, members 10 operated by the latter for causing said tripping lever to act, and a fixed member for normally preventing the operation of the said members.

AMOS ACKLEY.
S. HAINES PLUM, 2d.
